UNITED STATES PATENT OFFICE.

FRANK E. EWELL, OF BRIDGEWATER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PASTING MECHANISM FOR SHOE MACHINERY.

1,278,449.

Specification of Letters Patent. Patented Sept. 10, 1918.

Application filed December 28, 1915. Serial No. 68,993.

To all whom it may concern:

Be it known that I, FRANK E. EWELL, a citizen of the United States, residing at Bridgewater, in the county of Plymouth 5 and State of Massachusetts, have invented certain Improvements in Pasting Mechanism for Shoe Machinery, of which the following description, in connection with the accompanying drawings, is a specification, like reference characters on the drawings indicating like parts in the several figures.

This invention relates to mechanism for applying paste to parts of boots and shoes 15 and is herein shown as embodied in a machine for attaching heels and toplifts.

One object of the present invention is to provide paste applying mechanism so constructed and arranged as to be operated in 20 the regular cycle of the machine for applying the desired amount of paste to a blank at the proper time and without requiring attention or effort on the part of the operator.

25 It is desired to apply paste to the surface of a toplift after a heel has been nailed to the shoe and just before the toplift is spanked upon the projecting ends of the attaching nails. In machines for attaching 30 heels and toplifts it is customary to provide a movable nail loading device for delivering the attaching nails to the nail receiving passages of the die plate. The loading device must be moved preliminarily to each 35 heel attaching operation. One important feature of the present invention consists in paste applying mechanism including a movable applying device constructed and arranged to be controlled by the movement

40 of the loader. Such an arrangement is advantageous in that the actuation of the paste applying device is effected by a motion of the operator which is already necessary in the regular operation of the machine so 45 that no additional effort is required and the operation of the machine is not delayed. Moreover, by the employment of such mechanism the application of the paste is made to occur at the most favorable moment in the cycle of the machine; viz., when 50 the heel and toplift have been placed in the holder and just before the attaching operation.

Another feature of the invention consists

in a paste applying device including a movable plate or pad constructed and arranged so that its applying face enters the paste disposed downwardly when the device is moved into paste receiving position. It results from such an arrangement that the 55 entire paste applying face is coated with paste so that a uniform quantity of paste will be applied to each lift. Heretofore this has not always been the case because it is customary to use a viscous paste which 60 flows too slowly to coat the surface of an applying device when dipped into the paste with but short intermissions between successive attaching operations.

The features above discussed and others 65 incident to the invention will be best understood and appreciated from the following description of a preferred embodiment thereof selected for purposes of illustration and shown in the accompanying drawings, in which,—

Figure 1 is a view of portions of a heel attaching machine in which the present invention is embodied;

Fig. 2 is a sectional view of parts shown 80 in a portion of Fig. 1, and

Fig. 3 is a view in perspective showing a toplift with a portion of the paste applying device.

The invention is herein illustrated as disclosed in the American Lightning Nailing Machine shown fully in the application of J. H. Pope, Serial No. 81,873, filed March 3, 1916. It will be apparent, however, that the invention is not limited in its application to this or to any particular type of 85 nailing or attaching machine.

In the drawings, a portion of the frame 8 is shown to which is secured a stationary die plate 12 having nail receiving passages 13. 90 Beneath the die plate 12 is disposed a jack 10 for the shoe to be heeled and mechanism, not shown, is provided for elevating the jack to bring the shoe and heel into engagement preliminarily to the attaching operation. The frame 8 is provided with vertical bearings for a pair of side rods 16 which, as shown in the application above mentioned, are arranged to carry a gang of 95 drivers 14.

The attaching nails are supplied to the nail receiving passages 13 of the die plate by a loader or nail carrier 28 mounted to swing in

a horizontal plane about one of the side rods 16. The loader 28 is located initially in its outer position as shown in dotted lines in Fig. 1 where it is readily accessible to be supplied with attaching nails delivered from any suitable nail distributing mechanism. The loader is provided with a handle 30 by which it is swung from nail receiving to nail delivering position by the operator. In Fig. 10 1 the loader is shown as having moved through about two-thirds of its path toward nail delivering position.

Secured to the rear of the die plate 12 is a plate 18 upon the lower surface of 15 which is mounted an oscillatory holder for heel and toplift blanks. The holder includes a pair of toplift engaging fingers 24 and a pair of heel-engaging fingers 26 both of which are arranged to swing about a stud 20 22 as an axis. The stud 22 is carried by an adjustable slide disposed below the plate 18 and to be regulated in its position from front to rear by an adjusting screw 20. The holder also includes a flat spanker plate 25 which extends over the toplift holding fingers 24 and engages the tread surface of the toplift from the time the latter is presented to the holder until it is removed from the machine with the shoe at the conclusion of 30 the attaching operation. It will be understood that the toplift blank is supplied to the toplift holding fingers 24 while the latter occupy a position at the front of the machine beneath the nail receiving passages 35 13. The holder is then moved by the operator into the position shown in Fig. 1 where- 40 in the heel holding fingers 26 occupy a position beneath the nail receiving passages and the toplift holding fingers are located in a position 90° removed from attaching position.

The paste reservoir 60 is mounted upon the frame at the rear of one of the side rods. It comprises an elongated trough 45 having a cover with a hinged section 62 whereby paste may be supplied to the reservoir. The inner end of the reservoir 60 is disposed substantially beneath the toplift when the heel and toplift holder is arranged 50 to hold the heel blank beneath the nail receiving passages.

The cover of the reservoir 60 is provided with a bracket 51 in which is pivoted a lever 54 carrying at its free end a pivotally 55 mounted plate or pad 58. The cover of the reservoir is cut away to permit the passage of the lever 54 and the paste applying plate. The lever 54 is offset rearwardly between its fulcrum and the pad 80. Its short arm is 60 pivotally connected to a head 50 from which projects a threaded shank 44 by means of which the lever 54 is oscillated.

Motion is transmitted to the shank 44 to swing the lever of the paste applying mech- 65 anism by connections with the movable

loader arm 28 above described. At the rear of the die plate 50 are provided bearings for a horizontally reciprocating bar 38 having an upwardly projecting pin 36 which is arranged to enter a cam slot 34 formed in a cam arm 32 integral with the loader 28. The cam slot 34 is so shaped that when the loader 28 is swung from nail receiving position to nail delivery position the bar 38 will be moved toward the left, Fig. 1, during the first part of the movement of the loader and then held at rest while the pin 36 moves in a substantially concentric portion of the slot. During the latter part of the return movement of the loader the bar 38 is moved 80 in the opposite direction. Secured to the left end of the slide bar 38 is a downwardly projecting bracket 40 having an adjustable arm 42 perforated to receive loosely the threaded shank 44. The arm 42 of the bracket may be moved at substantially right angles to the bar 38 for purposes of adjustment and then clamped in adjusted position. The shank 44 is provided with stop nuts 46 and 48 upon either side of the bracket arm 42. These nuts are set to afford a lost-motion connection between the slide bar 38 and the shank 44 and it will be apparent that the length of this connection may be adjusted as desired. 95

The paste applying plate 58 which is carried by the outer arm of the lever 54 has also a pivotal connection to the reversing link 56 which is pivoted to a lug on the cover of the reservoir 60 to turn about an axis eccentric to the fulcrum of the lever 54. The construction and arrangement of the link 56 and lever 54 is such that the plate 58 is reversed in position as the lever 54 is moved from paste receiving to paste applying position. As shown in Fig. 2, the plate 58 is moved downwardly into the paste in the reservoir 60 with its applying face in advance or downwardly disposed and is therefore completely coated with paste. When 110 the lever 54 is swung upwardly the position of the plate 58 is reversed and it comes into engagement with the toplift disposed upwardly and in substantially horizontal position. 115

By arranging the face of the paste applying plate 58 to be disposed downwardly as it enters the paste it will be noted that a relatively small amount of paste in the reservoir will be sufficient to entirely coat the 120 face of the applying plate. Moreover this arrangement permits the applying face to be brought into close proximity to the bottom of the reservoir with the result that the paste is applied uniformly even though its level in the reservoir becomes very low. 125

The operation of the above mechanism will doubtless be clear from the foregoing description but may be briefly outlined as follows. The machine comes to rest after 130

the operator has attached both the heel and toplift to a shoe with the toplift holding fingers 24 at the front. The operator then inserts a toplift blank and turns the holder 5 into the position shown in Figs. 1 and 2 of the drawings, thus bringing the toplift into position above the reservoir 60. A heel blank is then placed in the heel holding fingers 26 and nails are supplied to the 10 loader 28. The operator now swings the loader 28 inwardly as indicated by the arrow in Fig. 1 in order to deliver the nails to the nail receiving passages 13. In this movement of the holder the bar 38 is moved to 15 the left and the paste applying plate 58 elevated into contact with the underside of the toplift as indicated by dotted lines in Fig. 2. It is held momentarily in contact with the top lift while the pin 36 is in the 20 concentric portion of the slot 34 in the loader. The loader 28 is then moved reversely whereupon the arm 42 of the bracket 40 engages the stop 48 on the shank 44 and swings the paste applying lever 54 down- 25 wardly reversing the position of the paste applying plate 58 and bringing it to rest in the paste in the reservoir. The holder is then turned to bring the pasted toplift into attaching position whereupon the cycle 30 may be repeated.

Having thus described my invention, I claim as new and desire to secure by Letters Patent of the United States:

1. A machine for operating on heels, having, in combination, a movable nail carrier, a die plate arranged to be supplied thereby, a blank holder, and a paste applying device operated by the nail carrier for supplying paste to a blank in the holder.

2. A machine for operating on heels, having, in combination, a movable nail carrier, a die plate arranged to be supplied thereby, a blank holder, and a paste applying device responsive to the movement of the nail 45 carrier.

3. A machine for operating on heels, having, in combination, a stationary die plate, a nail carrier movable from nail receiving position to nail delivering position, a blank holder, and a paste applying device constructed and arranged to be operated by the nail carrier in its movement to delivering position.

4. A machine for operating on heels, having, in combination, a die plate having nail receiving passages, a movable loader, a holder constructed and arranged to supply first a heel blank and then a toplift in alignment with the passages of the die plate, and a paste applying device connected with the loader and operated to paste the toplift when the loader delivers nails to the die plate for attaching the heel blank.

5. A machine for operating on heels, having, in combination, a die plate having nail

receiving passages, a loader movable laterally to transport nails to the die plate, a blank holder, and a vertically movable paste applying device responsive to the movements of the loader.

6. A machine for operating on heels, having, in combination, a horizontally disposed die plate, a nail loader movable above the die plate, a blank holder movable below the die plate and independently thereof, 75 and a movable paste applying device operatively connected to the loader.

7. A machine for operating on heels, having, in combination, a nail loader and a blank holder both mounted to turn about 80 substantially vertical axes, and a vertically movable paste applying device controlled in its movements by the loader.

8. A machine for operating on heels, having, in combination, a nail loader and a 85 blank holder both mounted to turn about substantially vertical axes, a movable device for applying paste to a blank in the holder, and connecting mechanism including a reciprocatory bar operated by the 90 loader and operating the paste applying device.

9. A machine for operating on heels, having, in combination, an oscillatory paste applying device, and operating mechanism 95 therefor including a reciprocatory bar having a lost-motion connection with the pasting device, and means for adjusting the length of the lost-motion connection to regulate the paste applying movement of the 100 pasting device.

10. A machine for operating on heels, having, in combination, a paste reservoir, a blank carrier movable in a path above the reservoir, a paste applying device including 105 a lever pivoted for movement between the reservoir and the carrier and having at its free end a pivotally mounted plate arranged to be automatically turned on the lever in approaching its paste applying position, 110 and means for automatically turning the plate on the lever as it approaches paste applying position.

11. A machine for operating on heels, having, in combination, a paste reservoir, a 115 blank carrier, and a paste applying device including a lever pivoted for movement between the reservoir and carrier and having a movable plate at its free end constructed and arranged to be brought into parallel relation to a blank in the holder in the paste applying operation, and means for automatically turning the plate on the lever, to bring it into such parallel relation.

12. A machine for operating on heels, 125 having, in combination, a paste container, a blank carrier, and a paste applying device including a lever pivoted for movement between the container and carrier, a pivoted plate mounted on the lever, and means act- 130

ing automatically for reversing the position of the plate on the lever in its movement from the blank to the container.

13. A machine for operating on heels, having, in combination, a paste container, a blank carrier, and a paste applying device including a pivoted lever, and a flat paste applying plate mounted on the lever and movable on the lever to enter the paste in the container with its blank engaging face downwardly disposed and to engage a blank in the carrier with said face upwardly disposed.

14. Paste applying mechanism for a heel-
ing machine including a paste reservoir, a lever pivoted above the reservoir, a plate pivoted to the end of the lever, and a reversing link pivoted to the plate at one end and eccentrically with respect to the fulcrum of the lever at the other.

15. Paste applying mechanism for a heel-

ing machine including an actuating bar, a swinging paster, and connections including a head having a shank disposed parallel to the bar and carrying adjustable stops, and a bracket on the bar perforated to receive the shank and mounted for adjustment at right angles to the bar.

16. A machine for operating on heels, having, in combination, a die plate, a nail loader movable toward and from the die plate for transporting nails thereto, means for presenting a blank to the die plate, and a paste applying device connected to the loader and arranged to be moved into engagement with the blank and then held stationary against the blank by the continued movement of the loader into nail delivering position.

In testimony whereof I have signed my name to this specification.

FRANK E. EWELL
